UNITED STATES PATENT OFFICE

165,594

GRADER

John G. Macdonald, Goderich, Ontario, Canada

Application April 22, 1950, Serial No. 9,427

Term of patent 14 years

(Cl. D14—3)

To all whom it may concern:

Be it known that I, John G. Macdonald, a citizen of Canada, and resident of the town of Goderich, county of Huron, Province of Ontario, in the Dominion of Canada, have invented a new, original, and ornamental Design for a Grader, of which the following is a specification, reference being had to the accompanying drawings that form part thereof.

In the drawings:

Figure 1 is a side elevational view of my new design for a grader, the opposite side being similar to the side shown.

Figure 2 is a front elevational view of the grader.

Figure 3 is a rear elevational view.

Figure 4 is a perspective view taken from above and from one side at the rear of the grader.

I claim:

The ornamental design for a grader, as shown and described.

JOHN G. MACDONALD.
